WILLIAM M. HORN, OF DETROIT, MICHIGAN, ASSIGNOR TO HORACE E. DODGE BOAT & PLANE CORPORATION, OF NEW YORK, N. Y., A CORPORATION OF DELAWARE

CLUTCH CONTROL MECHANISM

Application filed February 20, 1930. Serial No. 430,013.

This invention relates to the control for the clutch associated with the propelling motor of a motor-boat or speed boat, especially of the type wherein the propelling motor is located astern of the driver's seat.

In existing constructions, the control is of such a nature that the operator cannot always maintain a position observing his course ahead and the parts obstruct the floor or cockpit in front of the driver's seat. Realizing these drawbacks, it is the prime aim of the present invention to provide a construction or control having operating means in the line of vision, while observing the course ahead and which permits such connection to be made with the clutch that the space between the toe board and driver's seat will be unobstructed so as to materially add to the comfort of the driver and passengers and as well enable more ready maneuvering of the craft.

A further object is to provide a novel construction wherein oppositely movable rods are mounted out of obstructing relation for rectilinear travel and are connected by a relatively large upstanding lever located forwardly of the toe board.

A further aim is to provide the handle rod of such a nature that it passes through the instrument board and terminates in and is operable from a zone relatively close thereto and is constantly observable while viewing the course straight ahead.

Various additional objects and advantages will become apparent from a consideration of the description following, taken in connection with accompanying drawings illustrating an operative embodiment.

In said drawings:—

Fig. 1 is a fragmentary longitudinal sectional view taken through a speed boat equipped with my invention;

Fig. 2 is a plan view of the parts of Fig. 1;

Fig. 3 is a cross sectional view taken on the line III—III of Fig. 1;

Fig. 4 is a cross sectional view taken on the line IV—IV of Fig. 1; and

Fig. 5 is a sectional view taken on the line V—V of Fig. 1.

Referring specifically to the drawings, 10 50 designates a conventional motor or speed

boat. The propelling motor for such boat is carried thereby at 11 and extending therefrom is the housing 12 which contains the clutch adapted to occupy a position in neutral, or positions to cause the motor to propel the vessel forwardly or reversely. The driver's seat is shown at 13 within a cockpit 14. The floor in the cockpit is designated 15, the toe board as 16, the dash as 17 and the instrument board as 18. One or more longitudinal beams or timbers 19, forming part of the frame of the boat, support the floor 15, the seat 13 and the motor 11.

The clutch within casing 12 is controlled by a transverse rock shaft 20 which has a depending crank 21 keyed thereto and located exteriorly thereof. A link or connecting rod 22 is pivoted at 23 to said crank 21 and is located between the bottom of the vessel and the floor 15. At the forward end, said rod 22 is pivoted at 24 to an upstanding lever 25 which, in turn, is pivoted on a horizontal shaft 26 in bearings 27 fastened to the beams or sills 19.

Said lever 25 is relatively high and has its axis much closer to the bottom than to the top thereof so that slight power will suffice to operate the clutch.

The operating rod or handle for the clutch is shown at 28 and is disposed in parallelism to the rod 22 and adapted to move substantially rectilinearly with the latter but in an opposite direction, the operating rod being pivoted as at 29 to the upper end of said lever 25. It will be noted that the said operating rod 28 passes through openings 30 and 31 provided in the instrument board 18 and dash 17, respectively, the openings being of such size as to provide the requisite clearance for such operation. At the free end of the operating rod 28, it is equipped with a knob 32 which is located relatively close to the instrument board and in a position to be readily grasped by the operator. Thus the operation of such rod does not require the operator to bend forwardly or remove his eyes from the course ahead, which greatly adds to safety in operation.

When the clutch is in a neutral position, the rod 28 is in the full line position indicated

in Fig. 1. Such rod is adapted to be pushed forward to the dotted line position indicated at 33 which correspondingly moves the connected parts so as to shift the clutch into a 5 position where the operation of the motor will cause forward propulsion of the boat. Such operating rod 28 is also adapted to be pulled rearward into the dot-dash line position 34, which correspondingly moves the 10 connected parts so that the clutch engages the motor to connect the propeller for reverse driving or propulsion of the boat.

As a result of the invention, it will be seen that the entire space of the cockpit forwardly 15 of the seat, between the sides of the boat and below the instrument board, is unobstructed so that the driver may more dexterously maneuver the boat and especially operate a means substantially in the line of vision and 20 while maintaining his body and head normally erect, namely the rod 28, to shift the clutch. At the same time, the more accessible knob 32 is adapted to be pushed forward or pulled rearward to control the direction 25 of propulsion with minimum effort.

Various changes may be resorted to provided they fall within the spirit and scope of the invention.

I claim as my invention:

30 1. In combination with a boat hull having an engine compartment and a driver's compartment forward thereof, the driver's compartment having a floor spaced from said boat hull, a toe board and dash closing the 35 forward end of said driver's compartment, steering mechanism extending into said driver's compartment, a longitudinally movable rod extending through said dash adjacent the upper edge thereof, means for supporting the rearwardly extending portion of 40 said rod adjacent said steering mechanism, lever mechanism positioned forward of said dash, said last named mechanism comprising a pivot member, a lever mounted thereon, means extending rearwardly beneath the floor 45 of said driver's compartment for connecting the lower end of said lever to the clutch of said engine, and means for operatively connecting the forward end of said longitudinally movable rod to the upper end of said lever.

2. In combination with a boat hull having spaced longitudinally extending beams, an engine supported by said beams, a compartment forward of said engine having the floor thereof supported by said beams, a toe board and dash forming a closure for the forward end of said compartment, steering mechanism extending through said forward closure into said compartment, a longitudinally movable operating rod extending rearwardly through said dash adjacent the upper portion thereof, means for supporting said rod adjacent the steering mechanism, a lever positioned forward of said compartment,

70 pivot means for said lever carried by said beams, means positioned beneath the floor of said compartment and extending longitudinally of said hull for connecting the lower end of said lever to the clutch mechanism of said engine, and means for pivotally connecting said longitudinally movable rod to the upper end of said lever.

3. In combination with a boat hull having an engine compartment and a driver's compartment having a floor located adjacent the bow of said hull, a pair of longitudinally extending beams beneath said driver's compartment forming a support for the floor thereof, means for closing the forward end 80 of said compartment, comprising a toe board and a dash, steering mechanism extending within said compartment, a clutch operating rod having one end supported adjacent said steering mechanism and the opposite end extending through said dash, a lever movable in the direction of length of the said hull and pivotally mounted within the bow of said hull forward of said dash, means for operatively connecting said operating rod to 85 one end of said lever, a reach rod pivotally connected to the lower end of said lever, said reach rod passing rearwardly beneath the floor of said compartment, and means for operatively connecting said reach rod to the 90 clutch mechanism of said engine.

In testimony whereof I affix my signature.

WILLIAM M. HORN.
